UNITED STATES PATENT OFFICE.

WALTER SCOTT, OF PLAINFIELD, NEW JERSEY; ISABELLA SCOTT AND DAVID JOHN SCOTT EXECUTORS OF SAID WALTER SCOTT, DECEASED.

PRINTING-MACHINE.

1,058,017.

Specification of Letters Patent.

Patented Apr. 1, 1913.

Application filed March 30, 1906. Serial No. 308,839.

To all whom it may concern:

Be it known that I, WALTER SCOTT, a citizen of the United States of America, and a resident of Plainfield, Union county, New Jersey, have invented certain new and useful Improvements in Printing-Machines, of which the following is a specification.

The present invention relates generally to printing machines, and has more particularly reference to tripping mechanism associated therewith, and to the general arrangement of the parts.

The object of the invention is the production of a structure of a compact and convenient form, and wherein the parts are easily accessible for the purpose of repairing or otherwise manipulating the same.

Another object of the invention resides in providing suitable tripping mechanism for the inking apparatus and form rolls when the impression remains tripped.

The invention accordingly consists in arranging the impression and form carrying cylinders one above the other but out of vertical alinement so as to expose a portion of the upper surface of the form carrying cylinder for the form rolls to rest upon, the inking apparatus being arranged upon the same side as the form rolls, leaving the other side of the form carrying cylinder exposed, which is of great advantage, especially in planographic machines. Preferably a printed side up delivery mechanism is arranged in front of the impression cylinder, and the form carrying cylinder is located below the impression cylinder but out of vertical alinement therewith and extends forwardly under the delivery mechanism, leaving an exposed portion on the upper surface of the said form cylinder on which the form rolls rest. This leaves the rearwardly facing portion of the two cylinders exposed, so that the pressman can wipe or dampen the form or otherwise manipulate the design without danger of being caught in the moving parts. Means are further provided for moving the inking apparatus away from the form rolls, and for lifting the latter independently of the inking apparatus, so that access can readily be had to both sides of both of the cylinders. The water rolls are located adjacent to the underside of the form carrying cylinder, and can, if desired, be raised and

lowered into and out of contact with the form cylinder once to every two revolutions 55 of the said form cylinder.

In multirevolution machines, automatic means are provided for tripping and untripping the impression once to a number of revolutions, and in order to obtain an evenly 60 printed product, the inking apparatus should be geared to supply ink to the form once to each cycle of the machine. When a sheet is missed in feeding, or if a sheet is fed out of register it becomes necessary to maintain 65 the impression tripped in order to prevent the form from placing ink on the blanket of the impression cylinder. For this purpose there is an interrupting means for the automatic means aforesaid, which, when set in 70 motion by a suitable actuating device, interrupts the operation of the automatic means aforesaid and maintains the impression tripped. This actuating device is under the control of the operator as by means of a foot 75 treadle or the like, or if an automatic feeding apparatus is used, under the control of the latter. The claims herein should be construed to cover both forms. When the impression remains tripped the ink will accumulate on the rolls and on the form, and for this reason there is provided in the present structure, in connection with the actuating device, means for stopping the supply of ink 80 and means for lifting the form rolls off the 85 form when the impression remains tripped. At the same time, the parts are so constructed that the impression can remain tripped and the form rolls be lifted without stopping the supply of ink, so that the ink 90 can be distributed before printing commences:

Other features of construction and combination of parts will appear as the specification proceeds.

In the accompanying drawings, the invention is embodied in a concrete and preferred form, but changes of construction may of course be made, and parts omitted, without departing from the spirit of the 100 invention.

In the said drawings: Figure 1 is a side elevation of a machine embodying the invention. Fig. 2 is a plan view of Fig. 1 with the cylinders and inking apparatus removed. Fig. 3 is an end view of Fig. 2

looking in the direction of the arrow 3 with parts broken away and omitted. Fig. 4 is a detail view of the means for stopping the supply of ink.

5 Similar characters of reference indicate corresponding parts in the different views.

1 indicates a framework of any suitable construction for properly mounting the parts composing the machine.

10 2 and 3 denote respectively the impression and form carrying members constituting the printing couple. For the purpose of certain claims these form and impression members could be of the bed and cylinder type, but 15 are shown here as of the rotary type. Toward the rear of the impression cylinder is located the feed board 4, and in front of the impression cylinder is the delivery mechanism indicated by the tapes 5. In the present instance, the impression and form cylinders are geared to make a number of revolutions to each impression, preferably two, and the impression cylinder is provided with the grippers 6 and the throw-off fingers 7 of 20 any ordinary or suitable construction, and operated by cams (not shown) or other means in the usual way to seize and release 25 the sheet at the proper periods.

The form cylinder is located below the 30 impression cylinder but out of vertical alinement therewith so as to extend forwardly away from the said impression cylinder and under the delivery mechanism. As will be noticed, this leaves an exposed 35 portion 8 on the upper surface of the said form cylinder, which is utilized for the location of the form rolls 9. In most machines, advantage is taken of the weight of the form rolls to aid in the distribution of 40 the ink, but where this construction is followed it has been customary to position the cylinders comprising the printing couple side by side, and to position the form rolls above the form cylinder. This results in an 45 arrangement of the cylinders and other parts which renders access to the form extremely difficult, and as it is of great importance in planographic machines that ready access should be had to the said form, 50 it will be appreciated how important and useful the present arrangement herein disclosed is. For it will be observed that in the structure herein disclosed, the advantages of ready access to the form, and of the most 55 effective positioning of the form rolls are combined. The said arrangement leaving an exposed portion 10 on the form cylinder facing toward the rear and adjacent to the feeder's platform 11. The water rolls are 60 located below the form cylinder as indicated at 12. It will also be noticed that that portion 13 of the impression cylinder which faces toward the rear is exposed so 65 for the purpose of make ready, &c., and so

that when the pressman is dampening the form his hand will not get caught as the cylinders are rotating away from each other.

In multirevolution machines, it is necessary to automatically trip and untrip the impression once to each cycle of the machines. This is usually effected by moving the impression cylinder into and out of contact with the form cylinder at certain intervals. The automatic means for tripping and untripping the impression take, in the present instance, the following form: The impression cylinder is mounted in eccentric bushings 14 which are connected to the rock-shaft 15 by means of the arm 16, rod 17 and lever 18, the parts being in duplicate and connections being made on both sides of the machine. Mounted on the shaft 19 is the cam 20 making one revolution to each impression. Engaging with this cam is the friction roll 21 of the pivoted lever 22 whose free end is provided with a friction roll 23. 24 is a connecting lever secured at one end by means of the arm 25 to the rock-shaft 15, while its other end is provided with the slot 26 having the recessed portion 27 in which the friction roll 23 engages. The rotation of the cam 20 will therefore, during the normal operation of the machine, cause the oscillation of the pivoted lever 22 and a reciprocating movement of the lever 24, whereby the rockshaft 15 will be oscillated, and the impression automatically tripped and untripped.

100 Interrupting means for the automatic tripping and untripping means are provided whereby the impression can be maintained tripped, if a sheet is missed in feeding, &c. In the present instance these interrupting means take the following form: 28 is a rocking and sliding cam provided at one end with a pin 29 extending in under the lever 24, and provided at its other end with a cam surface 30 which is adapted to come in contact with the pin or other member 31, conveniently mounted on the cam 20, when brought into the plane of the said pin 31. By this means the pin 29 lifts the lever 24, and the friction roll 23 slides through the slot 26 without reciprocating the said lever 24. In this way, the operation of the automatic means is interrupted and the impression remains tripped. The rocking and sliding cam 28 is mounted on the stud 32 which is slidingly mounted in the framework, and is normally held out of the plane of the pin 31 by reason of the spring 33 attached to the collar 34 and acting outwardly against the forked lever 35. The collar 36 limits the 110 outward movement of the forked lever.

115 The forked lever 35 is connected to a suitable actuating device, which latter, in the present instance, consists of the following elements: 37 is a rockshaft mounted in 120

70

the bearings 38 and connected to the foot treadle 39 in the feeder's platform by means of the horizontal lever 40, the vertical connection 41 and the centrally pivoted lever 42. When the foot treadle is depressed, it will 5 act to move the rocking and sliding cam 28 into the plane of the member 31. The form rolls 9 are mounted in suitable bearings 43 in the framework and can be lifted out of contact with the form by means of the cam arms 44 pivoted at 45 and adapted to act against the shanks 46 of the said form rolls. 10

47 denotes an inking apparatus composed, in this case, of the fountain 48, fountain roll 49, ductor roll 50, distributing drum 51 and distributing rolls 52. The parts composing the inking apparatus are mounted on the movable carriage 53 adapted to slide on the rollers 54 so as to be moved toward 15 and away from the form cylinder and the form rolls, whereby access can readily be had to the parts. The means for moving this carriage supporting the inking apparatus consist of the toggle links 55 and 56 and operating handle 57. The stops, 58 limit the movement of the carriage. The inking apparatus is geared to supply ink to the form once to each impression, that is 20 in the present instance, once to every two revolutions of the form cylinder. When the impression, however, is tripped beyond the normal period it is of course undesirable to have the ink accumulate on the distributing rolls and form. For this reason means 25 are provided for stopping the supply of ink when the foot treadle is depressed or the impression is otherwise maintained tripped, and also means for lifting the form rolls off the form. It is desirable, however, that 30 the parts should be so constructed that the ink can be distributed when inking up while the form rolls are raised off the form and while the impression is maintained tripped. In the present instance these several means 35 take the following form: Mounted loosely on the fountain roll shaft is a gear 59 having the clutch member 60 attached thereto. Mounted fast on the fountain roll shaft is a corresponding clutch member 61 which is adapted to slide on the 40 said shaft by reason of the key 62. Corresponding teeth and notches 63 are provided on the said two clutch members, which when in engagement cause the rotation of the gear 45 to be imparted to the shaft. Mounted on the stud 64 is a two armed lever 65 one end of which engages with the sleeve 66 moving with the clutch member 61. Mounted loosely on the stud 64 is the member 66^a engaging 50 with the cam 67. Carried by the lower arm of the lever 65 is the hollow projection 68 in which rests the spring 69 bearing against the member 66^a. When the cam 67 is turned in one direction, the member 66^a will 55 engage with the hollow projection 68 thereby causing the two clutch members to engage with each other. If the teeth and notches 63 are not in alinement with each other when the clutch is thrown in, power will be stored in the spring 69, and when the said teeth and notches coincide, the expansion of the spring will throw the members into engagement. When the cam 67 is moved in the other direction, the member 66^a will encounter the pin 70 on the lower arm of the lever 65 and 60 will throw the clutch members out of engagement. The teeth and notches 63 are however sufficiently long so that if the pin 70 is placed in the aperture 71, the member 66^a will not move the lever 65 sufficiently 65 far to cause the disengagement of the clutch members. It will therefore be seen that by turning the cam 67 in one direction the operation of the fountain roll will cease, but, that, if desired, the cam can be turned without stopping the operation of the said fountain roll. In the present instance, the ductor roll is conveniently operated from the cam 72 mounted on the fountain roll shaft by means of the arm 73 and friction roll 74. 70 By this means, when the rotation of the fountain roll ceases, the oscillation of the ductor roll will also cease. 75

In order to turn the cam 67 back and forth so as to trip and untrip the ink supply, connections are made to the automatic means for tripping and untripping the impression, the arrangement being such, however, that these means are rendered effective to trip the ink supply only when the actuating device for maintaining the impression tripped is set in motion. In this case these connections which may be termed the ink controlling means take the following form: Mounted upon the pin 75 in the 80 framework is the reciprocating connection 76 attached at its free end to the pivoted lever 22 by means of the bolt 77. Pivoted on the said reciprocating connection are two cam levers 78 and 79 connected by the 85 link 80 so that they will move up and down in unison. Moving with the cam 67 is an arm 81 having the friction roll 82. Mounted on the rock-shaft 37, and thus connected with, or forming part of, the actuating device, is the releasing member 83 upon which rests the cam lever 78. When the machine is normally running the two cam levers are held in their uppermost position and the reciprocation of the connection 76 will 90 produce no result in the operation of the machine. But, when the foot treadle is depressed the releasing member 83 will allow the cam levers to drop when the cam lever 79 moves in behind the roll 82, and will, on 95 the return stroke, carry the said friction roll with it, thus turning the cam 67 and stopping the supply of ink. So long as the foot treadle remains depressed, which can be done either by the operator keeping his 100

105

110

115

120

125

130

foot on the same, or by a locking device in a well known manner, the ink supply will remain tripped. But when the foot treadle is released and moves back, the cam lever 78 5 will move into the plane of the friction roll 82 and the inking operation will be resumed. Connected to the friction roll 82 is the arm 84 attached at its other end to the cams 85 mounted on the stud 86. These 10 cams 85 engage with the friction roll 87 on the lower end of the cam arms 44 so that simultaneously with the stopping of the ink supply the said form rolls will be raised out of contact with the form. If the 15 pin 70 is placed in the aperture 71 however, the form rolls will be lifted, but the ink supply will not stop.

The water rolls 12 are carried by a bracket 88 mounted on the bearings of the power 20 shaft 89 and can be moved toward and away from the form by means of the lever 90 operating the roll 91 engaging with the surface 92 of the bracket 89. The ductor roll 93 of the water rolls is shown as being 25 operated in this instance by means of the cam 94 on the shaft of the form cylinder through the instrumentality of the lever 95 and friction roll 96.

It is to be understood that although the 30 water rolls are shown movable from the form cylinder by hand lever only, that they can be moved by any well known cam device so as to contact with the form cylinder every second revolution. Also in cases 35 where the form cylinder has a part of its surface utilized as an ink distributing surface, the dampening rolls will be lowered out of contact with said surface every revolution automatically. This construction is 40 shown in Patent #758112.

The gearing employed in this machine is as follows: Starting with the power shaft 89, the pinion 97 mounted thereon drives the water rolls in any suitable and 45 well known manner such as is disclosed in Letters Patent 758112. The said pinion further meshes with the gear 98 on the form cylinder and with the gear 99 mounted on the stud 100. From this gear 99 motion is 50 imparted to the gear 101, pinion 102 and gear 103 on the shaft 19. The gear on the form cylinder meshes with the gear 104 on the impression cylinder, and with the gear 105 on the movable carriage of the inking 55 apparatus. The latter gear 105 transmits motion through the gear 106 and pinion 107 to the gear 59 on the fountain roll shaft. The form cylinder is further provided with a gear 108 of less pitch diameter than the 60 pitch diameter of the said form cylinder. From this gear the form rolls are driven by means of the intermediate pinions 109 in a manner similar to the construction shown in Patent 758112. The two upper rolls 110 resting on top of the form rolls proper and

movable therewith may be simply distributing rolls, or they may be vibrating rolls also as disclosed in the said Patent 758112.

What is claimed is:

1. In a printing machine, the combination 70 of a printing couple, consisting of a form and impression member, an inking apparatus, form rolls, automatic means for tripping and untripping the impression at regular intervals, means for interrupting the operation of the automatic means aforesaid so as to maintain the impression tripped, means for stopping the supply of ink, means for lifting the form rolls off the form, and an actuating device controlling the interrupting means, the ink supply stopping means and the form roll lifting means. 75

2. In a printing machine, the combination 80 with a printing couple consisting of a form and impression member, an inking apparatus having a fountain and fountain roll, means for operating the fountain roll, form rolls, automatic means for tripping and untripping the impression at regular intervals, means for interrupting the operation 85 of the automatic means so as to maintain the impression tripped, means for rendering the operating means for the fountain roll inoperative, means for lifting the form rolls off the form, and an actuating device controlling the interrupting means, the means for rendering the operating means of the fountain roll inoperative and the 90 form roll lifting means. 95

3. In a printing machine, the combination 100 with a printing couple consisting of a form and impression member, an inking apparatus having a fountain and fountain roll, means for operating the fountain roll, a ductor roll, means for operating the ductor 105 roll from the fountain roll, form rolls, automatic means for tripping and untripping the impression at regular intervals, means for interrupting the operation of the automatic means aforesaid so as to maintain 110 the impression tripped, means for rendering the operating means for the fountain roll inoperative, means for lifting the form rolls off the form, and an actuating device controlling the interrupting means, the means 115 for rendering the operating means of the fountain roll inoperative and the form roll lifting means.

4. In a printing machine, the combination 120 of a form cylinder, an impression cylinder superposed above the same but arranged out of vertical alinement with the form cylinder so as to expose a portion of the upper surface of the form cylinder, form rolls resting on the said exposed portion of 125 the upper surface of the form cylinder, an inking apparatus adjacent to the said form rolls, and means for moving the said inking apparatus away from the form rolls.

5. In a printing machine, the combina- 130

- tion of a printing couple consisting of a form and impression member, an inking apparatus, form rolls, automatic means for tripping and untripping the impression at regular intervals, means for interrupting the operation of the automatic means aforesaid so as to maintain the impression tripped, means for stopping the supply of ink having provisions whereby the said means can be rendered inoperative, means for lifting the form rolls off the form, and an actuating device controlling the interrupting means, the ink supply stopping means and the form roll lifting means.
5. In a printing machine, the combination of a form cylinder, an impression cylinder superposed above the same but arranged out of vertical alinement with the form cylinder so as to expose a portion of the upper surface of the form cylinder, form rolls resting on the said exposed portion of the upper surface of the cylinder, a cam arm supporting said form rolls pivoted at its upper end, and means for raising the lower 25 end of the cam arm.
6. In a printing machine, a form carrying member and an impression cylinder, a movable carriage, inking apparatus on the carriage, form rolls receiving ink from the inking apparatus but mounted independently of the movable carriage, means for moving the form rolls away from the form carrying member independently of the movable carriage, and means for tripping the impression, form rolls and inking apparatus.
7. In a printing machine, form carrying and impression cylinders arranged out of vertical alinement with respect to each other so as to expose the upper surface and the 30 rear surface of the form cylinder, a movable carriage, inking apparatus on the carriage, form rolls engaging the upper exposed surface of the form cylinder and receiving ink from the inking apparatus, and means for 35 tripping the form rolls and inking apparatus.
8. In a printing machine, form carrying and impression cylinders arranged out of vertical alinement with respect to each other so as to expose the upper surface and the rear surface of the form cylinder, a movable carriage, inking apparatus on the carriage, form rolls engaging the upper exposed surface of the form cylinder and receiving ink from the inking apparatus, and means for 40 tripping the form rolls and inking apparatus.
9. In a printing machine, the combination with a printing couple embodying form and impression members, of form rolls, an inking apparatus, a reciprocating member, cam members carried by said reciprocating member, means for controlling the operation of the inking apparatus and the form rolls, and means for positioning the cam members whereby upon the reciprocation of 45 said reciprocating member, said cam members will act upon the controlling means aforesaid to interrupt the operation of the inking apparatus and the form rolls.
10. In a printing machine, form and impression members, inking apparatus, means for controlling the operation of the inking apparatus, a reciprocating member, a cam member carried thereby, and an actuating device adapted to position said cam member 50 to cause the same, upon the movement of the reciprocating member, to engage the controlling means and interrupt the action of the inking apparatus.
11. In a printing machine, form and impression members, form rolls, means for lifting the form rolls off the form, a reciprocating member, a cam member carried thereby, and an actuating device adapted to position said cam member to cause the same, upon the movement of the reciprocating member, to cause actuation of said form rolls lifting means.
12. In a printing machine, a printing couple composed of form and impression members, an inking apparatus, automatic means for tripping and untripping the impression at regular intervals, means for interrupting the operation of the automatic means aforesaid so as to maintain the impression tripped, means for stopping the supply of ink, a reciprocating member, cam members carried by said reciprocating member, and an actuating device controlling the interrupting means and adapted to position the said cam members to engage and operate the means for stopping the supply of ink.
13. In a printing machine, a printing couple composed of form and impression members, form rolls, automatic means for tripping and untripping the impression at regular intervals, means for interrupting the operation of the automatic means aforesaid so as to maintain the impression tripped, means for lifting the form rolls off the form, a reciprocating member, cam members carried by said reciprocating member, and an actuating device controlling the interrupting means, and adapted to position the cam members to cause operation of the means for lifting the form rolls.
14. In a printing machine, a printing couple composed of form and impression members, an inking apparatus, form rolls, automatic means for tripping and untripping the impression at regular intervals, means for interrupting the operation of the automatic means aforesaid so as to maintain the impression tripped, controlling means for stopping the supply of ink, means for lifting the form rolls off the form, a reciprocating member, cam members carried by said reciprocating member, and an actuating device controlling the interrupting means and adapted to position the cam members to operate the ink supply stopping means and the form roll lifting means.
15. In a printing machine, the combination with the members of a printing couple, of automatic means for tripping and untripping the impression at regular intervals, an inking apparatus, a reciprocating member having a movement timed to correspond to that of the automatic tripping and untripping means, ink supply controlling 130

means for stopping and starting the supply of ink, two cams on the reciprocating member either of which may be brought into engagement with the ink supply controlling means, cam positioning means adapted to bring either cam into engagement with the ink supply controlling means, and an interrupting device for interrupting the operation of the automatic tripping and untripping means and for controlling the cam positioning means.

16. In a printing machine, the combination with the members of a printing couple, of automatic means for tripping and untripping the impression at regular intervals, an inking apparatus, ink supply controlling means adapted when shifted in opposite directions to start or stop the supply of ink, a reciprocating member timed to reciprocate once to each impression, cam members on the reciprocating member adapted to be positioned to engage and shift the ink supply controlling means in either direction, and means for positioning the cam members to engage the ink supply controlling means so as to start or stop the supply of ink.

17. In a printing machine, the combination with the members of a printing couple, of automatic means for tripping and untripping the impression at regular intervals, an inking apparatus, ink supply controlling means adapted when shifted in opposite directions to start or stop the supply of ink, a reciprocating member timed to reciprocate once to each impression, cam members on the reciprocating member adapted to be positioned to engage and shift the ink supply controlling means in either direction, means for positioning the cam members to engage the ink supply controlling means so as to start or stop the supply of ink, and an interrupting device for interrupting the operation of the automatic tripping and untripping means and controlling the cam positioning means.

18. In a printing machine, the combination with the members of a printing couple, inking apparatus, ink supply controlling means adapted when shifted in opposite directions to start or stop the supply of ink, a reciprocating member arranged to reciprocate in a relatively fixed path, cam members movably mounted on the reciprocating member adapted to be positioned to engage and shift the ink supply controlling means in either direction, and means for positioning

the cam members to engage the ink supply controlling means so as to start or stop the supply of ink.

19. In a printing machine, the combination with the members of a printing couple, form rolls, ink supply controlling means adapted when shifted in opposite directions to lift or lower the form rolls, a reciprocating member arranged to move in a relatively fixed path, cam members movably mounted on the reciprocating member adapted to be positioned to engage and shift the ink supply controlling means in either direction, and means for positioning the cam members to engage the ink supply controlling means so as to lift or lower the form rolls.

20. In a printing machine, the combination with the members of a printing couple, of automatic means for tripping and untripping the impression at regular intervals, form rolls, ink supply controlling means adapted when shifted in opposite directions to lift or lower the form rolls, a reciprocating member timed to reciprocate once to each impression, cam members on the reciprocating member adapted to be positioned to engage and shift the ink supply controlling means in either direction, means for positioning the cam members to engage the ink supply controlling means so as to raise or lower the form rolls, and an interrupting device for interrupting the operation of the automatic tripping and untripping means and for controlling the cam positioning means.

21. In a printing machine, the combination with the members of a printing couple, an inking apparatus, form rolls, ink supply controlling means adapted when shifted in opposite directions to start or stop the supply of ink and to lower or raise the form rolls, a reciprocating member arranged to move in a relatively fixed path, movable cam members on the reciprocating member adapted to be positioned to engage and shift the ink supply controlling means in either direction, and means for positioning the cam members to engage the ink supply controlling means so as to start or stop the inking operation.

Signed at New York this 26th day of March 1906.

WALTER SCOTT.
